(57) **CLAIM**

The ornamental design for a battery charger for a biomedical signal recorder, as shown and described.

DESCRIPTION

FIG. 1 is a front, top and right side perspective view of a battery charger for a biomedical signal recorder, showing our new design;

FIG. 2 is a rear, bottom and right side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a cross sectional view thereof, taken along the line 9-9 in FIG. 3;

FIG. 10 is a cross sectional view thereof, taken along the line 10-10 in FIG. 3;

FIG. 11 is a front view of the clip stand in opened position; and,

FIG. 12 is a right side view of the clip stand in opened position.

The broken line showing in FIGS. 9 and 10 of the interior surfaces of the battery charger for a biomedical signal recorder with a radio function illustrate portions of the battery charger for a biomedical signal recorder with a radio function which form no part of the claimed design.
